UNITED STATES PATENT OFFICE.

EDWIN Z. LESH, OF HARTFORD, CONNECTICUT.

DRAFTING INSTRUMENT.

1,127,033.

Specification of Letters Patent.

Patented Feb. 2, 1915.

Application filed September 17, 1912. Serial No. 720,792.

To all whom it may concern:

Be it known that I, EDWIN Z. LESH, a citizen of the United States, residing at Hartford, in the county of Hartford and State 5 of Connecticut, have invented a new and useful Drafting Instrument, of which the following is a specification.

My invention relates to a combination in one convenient instrument of the essential 10 elements of the 90° — 60° — 30° triangle, the 90° — 45° — 45° triangle and the protractor, three instruments commonly used in drafting, the object of which is a labor and time 15 saving device. This object is attained by the mechanism illustrated in the accompanying drawing in which:

M and N are two triangular parts shaped from any suitable material as wood, amber, sheet metal, etc.; the homologous edges *a* 20 and *b*, *c* and *d*, *e* and *f* of the triangles M and N respectively are equal; the homologous angles *g* and *h* are 30° each; the homologous angles *j* and *k* are 45° each; the triangle N has a projecting member Q, circular in shape, at the center of which a threaded stud, P is rigidly fixed to form a pivot for the triangle M, a corresponding portion of the triangle M being cut away to fit the projection Q, substantially as shown; 25 the stud P is located at a convenient point in the lines *e* and *f*, and equidistant from the vertices of the angles *j* and *k*, thus determining the axis of rotation of triangles M and N; the triangle N is provided with a protractor scale arranged concentric with the stud, pivot, or axis P; to the triangle M is rigidly fixed a plate L, of celluloid or other 30 suitable material, of irregular shape, designed to engage the pivot P, and provide a projecting member R, provided with a vernier scale adapted to indicate on the said protractor scale the degree of inclination between the edges *a* and *b*, when one member (M) has been revolved about P upon the 35 other member (N) substantially, as shown; P' is a thumb-nut, which engages the threaded stud P, and firmly fixes the two members M and N in any relative adjustment by binding the plate L against Q, the circular 40 projection of the triangle N. By this construction the members M and N are made to lie in the same plane.

The dash-and-dot lines represent the relative position of the triangles M and N when 45 the edges *e* and *f* are brought into coinci-

dence by revolving one member upon the other. In this position the edge *a* forms an angle of 90° with the edge *b*; the edge *c* makes an acute angle of 60° with the edge *b*, and the edge *d* likewise with the edge *a*, since 50 the sum of the angles of any triangle equals 180° ; the angles *s* and *t* are each equal to 45° being the acute angles of a right-triangle having equal legs; and the index reading of the protractor scale is 90° being the sum of 55 the two 45° angles *j* and *k* included between the edges *a* and *b*. Thus in one of its possible adjustments and by virtue of the inclination of the edges of its members with respect to each other, the instrument contains 60 at once a 90° , two 60° , two 45° , and two 30° angles, being all the essential elements of 65 the 90° — 60° — 30° and the 90° — 45° — 45° triangles, said members being adjustably combined in such construction as to constitute a protractor substantially as herein set 70 forth.

Since either of the edges *a* or *b* may be applied to the straight edge, T square, or otherwise used as a base from which to protect 80 any desired angle, the device is evidently very handy and convenient as a protractor.

The herein described device may be applied wherever either of the above mentioned triangles or a protractor can be used, 85 thus constituting in a practical sense a time and labor saving drafting instrument of universal application.

I claim:

In a drafting instrument two members of 90 suitable material (as celluloid), and right-angle triangular in shape, having their homologous edges and angles equal respectively, one acute angle of each member being 30° , the other 45° ; one member being 95 provided with a protractor scale, the other member having rigidly secured thereto a plate provided with a vernier scale adapted to indicate on said protractor scale the degree of inclination between certain homologous 100 edges of said members; the said members being pivotally articulated in such manner as to combine in triangular construction a 90° , two 60° , two 45° , and two 30° angles at 105 one possible setting of the said adjustable members.

EDWIN Z. LESH.
